BEARING AND PUMP OPERATING LEVER

James P. Ratigan, Los Angeles, Calif.

Application January 18, 1932, Serial No. 587,379

7 Claims. (Cl. 74—41)

This invention relates to an improved bearing and pump operating beam lever for an oil well pumping machine or the like.

This invention is an improvement on my co-pending application for "Bearing for pump operating lever", Serial No. 483,402, filed September 22, 1930.

It is the principal object of this invention to provide a sliding connection between the beam lever and the bearing of a pumping machine, which sliding connection will permit a limited longitudinal movement of the lever in relation to the bearing and which will prevent the lever from becoming detached from the bearing during any portion of the longitudinal movement thereof, and also providing means for securely locking the lever in a predetermined position with relation to the bearing.

The importance of the longitudinal movement of the beam lever in relation to the bearing resides in the ability to slide the lever from its normal operating position where the sucker or pump rod end of the lever is substantially directly over the pump barrel to a position where the pump rod end of the lever is sufficiently removed therefrom to permit the pump rod or other portions of the pumping structure to be readily removed without the necessity of having to dismantle the beam and bearing.

A further object of the invention is to provide the beam lever supporting bearing member with hooked shaped portions which may be cast integral therewith or suitably secured thereto for slidably engaging the flanged portion of an I-beam pumping lever or slidably engaging suitable runners secured to a wooden or other type of beam lever.

A further object of the invention resides in the arrangement of the parts whereby the lever may be shifted longitudinally without becoming detached or disconnected from the bearing, and also whereby the lateral shifting of the lever may be accomplished without disconnecting or dismantling any of the working parts or other portions of the machine, it being necessary only to release the locking means which retains the lever in its normal working position.

Further objects of this invention reside in the simplicity, ease of operation, and in the stability of the device, and also in the extremely low cost of applying the improvement.

The invention resides in the several combinations and associations of elements or groups of elements and mechanisms whereby the aforesaid objects and other objects and advantages which

will be apparent as the nature of the same is more fully understood from the following description and accompanying drawings wherein is set forth what is now considered to be a preferred embodiment. It should be understood, however, that this particular embodiment of the invention is chosen principally for the purpose of exemplification, and that variations therefrom in details of construction or arrangement of parts, may be effected and yet remain within the spirit and scope of the invention as the same is set forth in the appended claims.

In the drawings:

Figure 1 illustrates in full lines an elevation of the pumping machine to which the invention has been applied and in which the pumping beam or lever is locked to the bearing in operative position while the broken lines indicate the lever in its fully retracted position.

Figure 2 is an enlarged sectional view taken substantially along the line 2—2 of Figure 1 looking in the direction of the arrows.

Figure 3 is a plan view of Figure 2 in which the lever has been indicated by broken lines.

Figure 4 is a side view of Figure 3.

Referring to the drawings, Figure 1 illustrates the application of the invention to an oil well pump operating structure generally indicated at 1 which includes briefly a base 2 supporting a Samson post 3 braced by members 4 and 5. A driving mechanism 6 may be also mounted upon base 2 and is provided with crank discs 7 and wrist pins 8 upon which is journaled the bifurcated end of pitman 9.

Any suitable form or type of bearing 10 may be secured to the top of the Samson post 3, but I prefer to utilize that type of bearing illustrated and described in my co-pending application previously referred to, which is generally referred to as the rocker type bearing and the embodiment thereof which is utilized in this invention is illustrated in detail in Figures 2, 3 and 4. The bearing 10 includes two bearing members, the base member 11 and the rocker member 12.

The base member 11 is provided with a flat supporting surface 13 upon which the rocker member is adapted to roll, and depending therefrom are the flanges 14 by means of which, and suitable bolts not shown, the base member is secured to the Samson post.

The rocker member 12 is provided with a relatively long rocking surface 15 which is substantially cylindrical in form and adapted to roll back and forth upon the supporting surface 13 when the pump is being operated. The advan-

50
55

ages of this form of bearing are fully set forth in my copending application previously referred to. To prevent a relative slipping between the engaging surfaces of the bearing, the rocker member is provided with a stud 16 which loosely fits in the socket 17 formed in the base member. However, the stud and socket need not follow closely the form illustrated in the drawings but may take the form of gear teeth for one member 10 with suitable coacting depressions in the other member.

Preferably formed integral with the rocking surface 15 is the bridge member 18 which is supported above the rocking surface by supporting walls 19.

The beam lever 20 rests upon the bridge member 18 and is slidably secured thereto by hooked members 21 which, in the preferred embodiment, are cast integral with the rocker member but 20 may be otherwise secured thereto if desired.

As illustrated most clearly in Figure 2, the hooked members 21 are so positioned and of such shape as to loosely but securely connect the bearing rocker member to the beam lever, yet 25 having sufficient looseness to permit the lever to slide freely therethrough.

When a lever of other form, such as a wooden beam, is used, the beam may be provided with a metal plate to coact with the hooked members to 30 in the same way make a sliding connection.

It is desirable to limit the longitudinal sliding of the beam and for this purpose any suitable stop means may be used, or, as illustrated in Figure 1, a stop bracket 22 is suitably secured 35 upon the beam to stop further longitudinal movement thereof when the beam has reached the desired forwardly location whereat the horsehead 23 is in proper alignment with the sucker rod 24, at which point it is desirable to securely lock the 40 beam to the rocker member, and for that purpose the rocker member is provided with suitable bolt holes or slots 25 while the beam is provided with corresponding holes 26 through which the clamping bolts 27 are positioned.

By removing the bolts 27 the beam is freed to 45 slide to its retracted position as illustrated in broken lines in Figure 1. The limit of the backward sliding of the beam may be determined by a stop plate similar to the stop plate 22, but I 50 preferably utilize the horsehead brace member 28 for this purpose. As will be noted in Figure 1, the lever in its broken line position is prevented from further backward movement by the member 28 abutting against the forward end of the 55 rocker member 12.

To rock or operate the beam lever 20, the upper end pitman 9 is journaled in the usual way adjacent the rear end thereof. The pitman 9 also performs another important function, namely, to support the rear end of the lever 20 when 60 retracted to the position illustrated in broken lines in Figure 1.

Counterweights 29 may be positioned upon the rear of the beam lever 20.

To provide a connection between the forward end of lever 20 and the sucker rod 24, I prefer to utilize the horsehead construction illustrated in my copending application entitled "Equalizing beam hanger", Serial No. 587,380, filed January 18, 1932, which structure briefly includes the supporting bracket 30 suitably secured to the forward end of the lever to which the horsehead 23 is pivotally connected as at 31. The horsehead 70 is provided with an equalizing pulley 32 around which the cable 33 is carried while the ends 75

thereof are securely fastened in the crosshead 34 as at 35. The sucker rod 24 is clamped to the crosshead 34 in the usual manner. By the arrangement just described the sucker rod 24 is maintained in true alignment with the pumping barrel 35. The brace member 28 previously referred to acts to brace the lower end of the horsehead to the lever as clearly shown in Figure 1, and as previously described, it is this brace member 28 which acts as the stop to limit the 10 rearward sliding movement of the beam lever.

The pumping machine, as illustrated in full lines in Figure 1, is in its normal operating position, but occasionally it is necessary to remove the sucker rod from the pumping barrel 35, and 15 to do so the beam lever 20 together with the horsehead must be moved out of the way. Heretofore, it has been necessary to dismantle the pumping machine by removing the counterweights 29 from the rear end of the beam lever, 20 disconnecting the pitman 9, and also disconnecting the horsehead from the sucker rod and finally 25 parting the bearing 10 and then hoisting the lever out of position. To dismantle the pumping structure is expensive, requiring much labor 25 and time. By means of my invention the beam lever 20 may be easily and readily moved, merely requiring the removal of the bolts 27 and connecting the hoisting means to either of the eyelets 36 and sliding the beam lever rearwardly 30 until the brace member 28 abuts against the bearing rocker member 12. The pumping machine is now in the position indicated in broken lines in Figure 1, in which position it will be noted that the horsehead 23 has been removed 35 sufficiently to permit the sucker rod or the pump barrel to be withdrawn from the well. It will be appreciated that as the rear end of the beam lever is supported by the pitman that it is, therefore, not necessary to remove the counterweights 29 40 and also that even though the beam lever has been slid rearward with relation to the bearing 10 the lever is still securely connected thereto by means of the hooked members 21 and for that reason there is no danger of the lever falling off 45 the Samson post 3.

To return the beam lever to its operative position the lever is slid forward until the stop bracket 22 abuts the rear end of the rocker member 12, at which point the bolt holes in the lever 50 and rocker are in alignment and the bolts may be thus easily inserted and the beam again securely locked in a position whereat the horsehead 23 will be in appropriate alignment with the sucker rod 24.

To prevent parting of the bearing members 11 and 12 the flanges 37 are secured or formed integral with the member 11 through which pin 38 is securely mounted. Through the adjacent supporting walls 19 of the rocker 12 are arcuate 60 slots 39 through which the pin 38 extends, thus loosely locking the two bearing members together but permitting sufficient looseness to permit the necessary relative motion therebetween.

In a pumping machine in which my invention 65 is utilized the beam lever, whether in its forward, retracted or in any intermediate position, is at all times securely and safely retained therein.

While the invention has been described for use 70 in connection with a pumping machine, it is to be understood that it may be utilized with walking beam levers used for other purposes.

While I have illustrated the preferred form of my invention, it is to be understood that the foregoing description is for illustrative purposes 75

only, and I do not desire to be limited by any of the details shown, except as defined in the appended claims.

I claim:

5. 1. In a pumping machine, a bearing, a beam lever slidably mounted thereon, means for locking the beam to said bearing, and a pitman for operating said beam when in operative position and for supporting the rear end thereof when shifted to its retracted position.

10 2. In a pumping machine, a bearing, a beam lever slidably mounted thereon, stop means for limiting the sliding movement of the beam in relation to said bearing, means for locking the beam to said bearing, and a pitman for actuating said beam when in operative position and for supporting the rear end thereof when shifted to its retracted position.

15 3. In a pumping machine, a bearing, a beam lever slidably associated therewith, means mounted upon said beam for limiting the sliding movement thereof, means for locking the beam to said bearing, and a pitman pivotally connected to said beam in spaced relation from said bearing for actuating said beam when in operative position and for supporting the rear end thereof when shifted to its retracted position.

20 4. In a pumping machine, a bearing provided with a guide-way, a beam slidably mounted in said guide-way, means for locking the beam to said bearing, and a pitman pivotally connected to said beam at a point spaced from said bearing for operating said beam when in its operative position and for supporting the rear end thereof when the beam is shifted to its retracted position.

25 5. In a pumping machine, a bearing provided with a grooved guide-way, a beam having a flange slidably mounted in said groove, means for locking the beam to the bearing, a counterweight mounted upon the rear end of the beam, and a pitman pivotally connected to said beam at a point spaced from the bearing for operating said beam when in its operative position and for supporting the counter-weighted rear end of the beam when the beam is shifted to its retracted 10 position.

6. In a pumping machine, a bearing having a plurality of inwardly directed hook-shaped members, a beam having a flange formed along its lower edge adapted to be slidably mounted in 15 the hook members of said bearing, means for locking the beam to the bearing, and a pitman pivotally connected to said beam at a point spaced from the bearing for operating the beam when in its operative position and for supporting the 20 rear end of the beam when shifted to its retracted position.

7. In a pumping machine, a Samson post, a walking beam, bearing means pivotally connecting said walking beam upon said Samson post for movement between two positions, one in which the forward end of the walking beam is in alignment with the well and the other in which the walking beam is retracted to permit access to the well, and a pitman pivotally connected to 30 said beam at a point spaced from said bearing for operating said beam when in its forward position and for supporting the rear end thereof when the beam is in its retracted position.

35

JAMES P. RATIGAN.
